UNITED STATES PATENT OFFICE

159,470

BILLFOLD

Douglas J. Broughton, Springfield, Mass., assignor to Buxton, Incorporated, Springfield, Mass., a corporation of Massachusetts

Application September 2, 1949, Serial No. 4,827

Term of patent 14 years

(Cl. D87—3)

To all whom it may concern:

Be it known that I, Douglas J. Broughton, a citizen of the United States, residing at Springfield, Massachusetts, have invented a new, original, and ornamental Design for a Billfold, of which the following is a specification, reference being had to the accompanying drawing, forming a part hereof.

Referring to the drawing:

Fig. 1 is a top edge view; and

Fig. 2 is a front elevational view of a billfold showing my new design.

The back of the billfold, not shown, is substantially plain.

The dominant features of the design reside in the portions shown in full lines.

I claim:

The ornamental design for a billfold, as shown and described.

DOUGLAS J. BROUGHTON.
